CLAIM

The ornamental design for an set of alphanumeric letterboard characters, as shown and described.

DESCRIPTION

FIG. 1 is a front, top and side perspective view of the letterboard character “A”, showing my new design.

FIG. 2 is a side elevational view of the letter “A” showing my new design;

FIG. 3 is a plan view of the letter “A” showing my new design;

FIG. 4 is a plan view of the letter “B” showing my new design;

FIG. 5 is a plan view of the letter “C” showing my new design;

FIG. 6 is a plan view of the letter “D” showing my new design;

FIG. 7 is a plan view of the letter “E” showing my new design;

FIG. 8 is a plan view of the letter “F” showing my new design;

FIG. 9 is a plan view of the letter “G” showing my new design;

FIG. 10 is a plan view of the letter “H” showing my new design;

FIG. 11 is a plan view of the letter “I” showing my new design;

FIG. 12 is a plan view of the letter “J” showing my new design;

FIG. 13 is a plan view of the letter “K” showing my new design;

FIG. 14 is a plan view of the letter “L” showing my new design;

FIG. 15 is a plan view of the letter “M” showing my new design;

FIG. 16 is a plan view of the letter “N” showing my new design;

FIG. 17 is a plan view of the letter “O” showing my new design;

FIG. 18 is a plan view of the letter “P” showing my new design;

FIG. 19 is a plan view of the letter “Q” showing my new design;

FIG. 20 is a plan view of the letter “R” showing my new design;

(Continued)

FIG. 21 is a plan view of the letter "S" showing my new design;
 FIG. 22 is a plan view of the letter "T" showing my new design;
 FIG. 23 is a plan view of the letter "U" showing my new design;
 FIG. 24 is a plan view of the letter "V" showing my new design;
 FIG. 25 is a plan view of the letter "W" showing my new design;
 FIG. 26 is a plan view of the letter "X" showing my new design;
 FIG. 27 is a plan view of the letter "Y" showing my new design;
 FIG. 28 is a plan view of the letter "Z" showing my new design;
 FIG. 29 is a plan view of the symbol "/" showing my new design;
 FIG. 30 is a plan view of the symbol "\$" showing my new design;
 FIG. 31 is a plan view of the symbol "@" showing my new design;
 FIG. 32 is a plan view of the symbol "." showing my new design;
 FIG. 33 is a plan view of the symbol "," showing my new design;
 FIG. 34 is a plan view of the symbol "-" showing my new design;
 FIG. 35 is a plan view of the symbol "#" showing my new design;
 FIG. 36 is a plan view of the number "0" showing my new design;
 FIG. 37 is a plan view of the number "1" showing my new design;
 FIG. 38 is a plan view of the number "2" showing my new design;
 FIG. 39 is a plan view of the number "3" showing my new design;
 FIG. 40 is a plan view of the number "4" showing my new design;
 FIG. 41 is a plan view of the number "5" showing my new design;
 FIG. 42 is a plan view of the number "6" showing my new design;

FIG. 43 is a plan view of the number "7" showing my new design;

FIG. 44 is a plan view of the number "8" showing my new design; and,

FIG. 45 is a plan view of the number "9" showing my new design.

The broken line portions of the figures illustrate both environmental structure and unclaimed portions of the alphanumeric letterboard characters, neither of which forms a part of the claimed design.

FIGS. 2 and 3 are exemplary of the thickness of the other characters. The sides, bottom and rear of all letterboard characters are unornamented.

1 Claim, 6 Drawing Sheets
